UNITED STATES PATENT OFFICE.

ALLAN K. HEXTOR, OF CLEVELAND, OHIO, ASSIGNOR TO THE ALBE MANUFACTURING COMPANY, OF CLEVELAND, OHIO, A CORPORATION OF OHIO.

SPRING COVER.

Application filed June 10, 1925. Serial No. 36,095.

This invention relates to that class of devices known as vehicle spring covers and more particularly to the variety of such devices that are made of flexible material in the nature of a boot that is adapted to be drawn about the vehicle spring with its edges overlapped and connected together by suitable means. In applying such a cover to a vehicle spring having, as they usually do, a spring clip, it is necessary to cut the material adjacent the ends of the U-shaped member of the clip in such manner that said ends and the bolt connecting them may protrude through the cover and thus not interfere with the fit of the cover in the immediate vicinity of the clip.

This invention has to do more particularly with means applied to the cover for enclosing the protruding parts of the spring clip and for concealing the more or less unsightly opening that is made in the cover for the accommodation of the aforesaid clip parts.

The primary purpose of the invention, therefore, is to provide a comparatively simple and inexpensive means for accomplishing the aforesaid result in an efficient and highly satisfactory manner and which means is neat and attractive of appearance.

Among other objects comprehended by the invention and which will appear as this description proceeds is the provision of a spring cover incorporating a clip casing that is economical of manufacture, being preferably formed of sheet metal stampings, and which is particularly convenient of assembly and attachment to the flexible material whereof the body portion of the spring cover is made.

An embodiment of the invention is illustrated in the accompanying drawing wherein Fig. 1 is a fragmentary perspective view of a spring cover applied to a vehicle spring and incorporating the invention; Fig. 2 is a perspective view of the several parts comprising the invention in separated condition; and Fig. 3 is a transverse section through a spring and cover on the line 3—3 of Fig. 1.

Wrapped about the vehicle spring 1 is a cover 2 of flexible material, and the edges of the cover are suitably secured together as by means designated 3. So far as the present invention is concerned, any approved means may be employed for connecting the edges of the cover together. A portion of

the cover 2 is cut away, as indicated at 4, for the accommodation of the ends of the U-shaped clip and the bolt which connects said ends together. These well known standard parts of a vehicle spring are omitted from the illustration.

Disposed inside the cover 2, and designed to extend across the top of the vehicle spring and overhanging the sides thereof is a frame-like base 5. This base preferably consists of a sheet metal stamping and comprises side members 6 which have their ends turned downwardly and connected together through arcuate members 7. The members 6 and 7 are shown as provided with prongs 8 that are struck from the material of the base.

A casing 10 is designed for application to the outer side of the cover 2 and to fit over the protruding parts of the spring clip. As in the instance of the base 5, the casing 10 is desirably die formed from sheet metal and it comprises a transversely arched portion 11 that extends centrally throughout the length of the casing and from the lateral sides of which flanges 12 extend. The flanges 12 are in the same plane and their ends are turned downwardly as are also the ends of the arched portion 11. It will be observed that the flanges 12 and the ends of the arched portion 11 are formed complementary to the respective members 6 and 7 of the base 5. The cover 2 and the casing 11 are provided, respectively, with slots 15 and 16 through which the prongs 8 of the base are engaged, the prongs being turned over beyond the parts of the casing thereby to hold the casing and base firmly to the cover 2.

While this means of connecting the parts together is economical and effective, obviously, rivets or other securing means may be substituted therefor.

The invention, having thus been described, is claimed as follows:

1. A cover for use with vehicle springs having spring clips, said cover comprising a member of flexible material that is adapted to be wrapped about the spring and to conform to the shape thereof, the edges of said cover being connected together, the cover having an opening through which parts of the spring clip protrude, and a metal casing permanently secured to the cover and enclosing the protruding parts of the clip.

2. A cover for use with vehicle springs having spring clips, said cover comprising a member of flexible material that is adapted to be wrapped about the spring and to conform to the shape thereof, the edges of said cover being connected together, the cover having an opening through which parts of the spring clip protrude, a base inside the cover in the vicinity of the spring clip, a casing applied to the outer side of the cover for enclosing the protruding parts of the clip, and means extending through the material of the cover and securing the base and casing together.

3. A cover for use with vehicle springs having spring clips, said cover comprising a member of flexible material that is adapted to be wrapped about the spring and to conform to the shape thereof, the edges of said cover being connected together, the cover having an opening through which parts of the spring clip protrude, a base inside the cover in the vicinity of the spring clip, and a casing applied to the outer side of the cover for enclosing the protruding parts of the clip, the base and casing having, on the one hand, prongs, and on the other hand, slots, said prongs extending through the material of the cover and through said slots and turned over therebeyond to hold the parts together.

4. A cover for use with vehicle springs having spring clips, said cover comprising a member of flexible material that is adapted to be wrapped about the spring and to conform to the shape thereof, the edges of said cover being connected together, the cover having an opening through which parts of the spring clip protrude, a base in the nature of a frame disposed inside the cover and surrounding said opening, a casing applied to the outer side of the cover for enclosing the protruding parts of the spring clip, and means extending through the material of the cover and securing the base and casing together.

5. A cover for use with vehicle springs having spring clips, said cover comprising a member of flexible material that is adapted to be wrapped about the spring and to conform to the shape thereof, the edges of said cover being connected together, the cover having an opening through which parts of the spring clip protrude, a base in the nature of a frame disposed inside the cover and surrounding said opening, and a casing applied to the outer side of the cover for enclosing the protruding parts of the spring clip, the base having prongs, and the cover and casing having slots through which said prongs are extended, the prongs being turned over beyond the casing thereby to secure the parts together.

6. A cover for use with vehicle springs having spring clips, said cover comprising a

member of flexible material that is adapted to be wrapped about the spring and to conform to the shape thereof, the edges of said cover being connected together, the cover having an opening through which parts of the spring clip protrude, a frame like base disposed inside the cover and surrounding said opening, the base comprising elongated side members having their ends turned downwardly and connected together by members designed to extend about the sides of the spring clip, a casing applied to the outer side of the cover and comprising a transversely arched central longitudinal portion having its ends deflected downwardly, and flanges extending from the lateral edges of said portion and having their ends likewise turned downwardly, the arched portion of the casing enclosing the protruding parts of the spring clip, and means extending through the cover for securing the base and casing together.

7. A cover for use with vehicle springs having spring clips, said cover comprising a member of flexible material that is adapted to be wrapped about the spring and to conform to the shape thereof, the edges of said cover being connected together, the cover having an opening through which parts of the spring clip protrude, a frame like base disposed inside the cover and surrounding said opening, the base comprising elongated side members having their ends turned downwardly and connected together by members designed to extend about the sides of the spring clip, and a casing applied to the outer side of the cover and comprising a transversely arched central longitudinal portion having its ends deflected downwardly, and flanges extending from the lateral edges of said portion and having their ends likewise turned downwardly, the arched portion of the casing enclosing the protruding parts of the spring clip, the base having prongs and the cover and casing having slots through which said springs are adapted to be extended, the prongs being turned over beyond the casing to secure the parts together.

8. A cover for use with vehicle springs having spring clips, said cover comprising a member of flexible material that is adapted to be wrapped about the spring and to conform to the shape thereof, the edges of said cover being connected together, the cover having an opening through which parts of the spring clip protrude, a base inside the cover in the vicinity of the spring clip, a casing applied to the outer side of the cover for enclosing the protruding parts of the clip, and means securing the base and casing together.

In testimony whereof, I hereunto affix my signature.

ALLAN K. HEXTER.
